Application June 6, 1929, Serial No. 368,983

3 Claims. (Cl. 78—38)

This invention relates to presses and aims to provide apparatus of improved controllability, capable of rapid and efficient operation.

The nature of the invention may be readily understood by reference to one form of apparatus embodying the invention and illustrated in the accompanying drawing.

In said drawing:

Fig. 1 is a side elevation of the apparatus;
10 Fig. 2 is a vertical section taken on the line 2—2 of Fig. 1; and

Fig. 3 is a transverse section, more or less diagrammatic in character, of the actuating element and showing the direction of the forces 15 set up during the operation.

The illustrative apparatus is here shown as vertically arranged and equipped with dies 10 and 11 for either hot or cold rivet setting. The character of the dies obviously depends upon the 20 character of press work to be performed by the press, and for that purpose the dies are made removable. The stationary die 11 is appropriately mounted at the lower side of the jaw 12 in frame 13, which may be supported by a base 25 either in the vertical position shown or with the axis of the dies arranged horizontally. The movable die 10 is carried at the lower end of a die plunger 14 which operates within the housing 15, the latter in this case formed integrally with 30 frame 13.

The plunger actuating element is here shown in the form of a reciprocating cam or wedge 16 having a cam surface 17 with a contour designed to advance the plunger at the proper rates 35 during the various portions of its active or operative travel. To reduce friction the upper end of the plunger 14 is provided with a roll 18 which engages the cam surface 17. The reactive thrust set up during the advance of the element 16 is 40 assumed by an anti-friction device in the form of rollers 19 (two in the present case) engaging the opposite surface 20 of the wedge 16 and carried in the housing 21 (in this case likewise cast integrally with the frame 13) which encloses the 45 element 16 and the upper portion of the plunger 14. The upper surface 20 of the wedge is advantageously made as wide as possible—it is here shown substantially wider than the cam surface 16, see Fig. 2—so as better to distribute the pressure 50 against the rolls 19.

Cam actuating mechanism is here shown in the form of a piston plunger 22 operating within cylinder 23 connected to the flanged portion 24 of the frame 13. The piston 22 is actuated by an appropriate medium, air pressure in this in-

stance, and is provided with a control valve (not shown) for introducing the actuating medium on either side of the piston and for opening an exhaust port on the opposite side.

The cam surface 17 is here formed with a leading portion 25 having a rather abrupt angle to the axis or direction of travel of the plunger 14 and designed to effect a rapid initial movement thereof, and a portion 26 at a substantially less angle designed to effect the power movement 10 of the plunger. For example, in upsetting a rivet, the cam surface 25 causes the die rapidly to approach and engage the rivet, this portion of the movement requiring relatively little power. The heading of the rivet requiring substantially 15 greater power but little relative movement of the die, is effected by the surface 26. In the present case this surface is slightly curved, convex downwardly, thereby reducing the relative movement 20 of the die 10 as it approaches the end of its operation.

The return or separating movement of the plunger in the present case is advantageously effected by a spring 27 enclosed within housing 15 and surrounding a portion of the plunger 14 so 25 as to raise the latter upon the retreat of the wedge 16.

The axis of the cylinder 23, i. e., the direction of travel of the wedge 16, is advantageously arranged at an angle greater than 90° to the axis 30 of the plunger 14 in order to place the point of contact 28 (see Fig. 3) of the cam surface 26 with the roller 18 during the power portion of the stroke approximately at the axis of the plunger 14, thus minimizing the component of force trans- 35 verse to the plunger,—this component being expended wholly in friction and reducing the efficiency of the apparatus. In the present case the inclination of the axis of cylinder 23 is made great enough to bring the point of contact 28 40 slightly beyond the axis 29 of the plunger to neutralize the transverse thrust caused by the friction of the roll 18 under the lateral pressure of the wedge. In other words, the line of force transmitted by the wedge 16 to plunger 14 (during the 45 power portion of the stroke) corresponds substantially to the line 30. The horizontal or transverse component (represented in amount and direction by the line 31) is approximately equal to the transverse component, in the opposite direction, created by the friction of the roll 18 under the lateral thrust of the wedge, and, therefore, neutralizes such force. The resultant force, represented substantially in amount and direction by the line 29, lies approximately along 50 55

or parallel to the plunger axis. By this arrangement, the maximum efficiency is produced and there is a minimum frictional loss attributable to the transmission of force from the transversely moving wedge to the plunger.

The illustrative mechanism is capable of rapid though accurately controlled operation, the contour of the wedge being designed to effect a nice determination of the speed and power portions of the die stroke and the relative travel necessary for each. All moving parts of the apparatus likely by any chance to cause injury to workmen may be fully enclosed. The end of the wedge which on the forward portion of its stroke projects beyond the housing 26 is shielded by a removable cover 32. This cover may be readily removed to expose important parts of the actuating mechanism.

Obviously the invention is not limited to the details of construction of the illustrative mechanism since these may be variously modified. Moreover, it is not indispensable that all features of the invention be used conjointly, since they may be employed in various different combinations and sub-combinations.

Having described one embodiment of our invention, we claim:

1. A wedge press of the character described, comprising in combination, a reciprocating press plunger, a reciprocating wedge having a cam surface engaging said plunger for moving the latter longitudinally, and wedge guiding means arranged to guide said wedge in a path at an angle greater than 90° relative to the line of plunger travel so that on the power stroke said wedge moves transversely of said plunger slightly in the direction of the power stroke of said plunger, thereby engaging said plunger closely adjacent the line of the plunger axis.

2. A press of the character described, compris-

ing in combination a press frame, a reciprocable press plunger operating in said frame, guiding means in said frame for guiding said plunger to reciprocate in a straight line, an anti-friction roller at one end of said plunger, a plunger actuating wedge engaging said roller, wedge reciprocating means arranged to cause said wedge to travel across said roller to advance the plunger on its power stroke, wedge guiding means, said wedge reciprocating and guiding means being carried by said frame at an angle to the plunger axis inclined in the direction of the power stroke of said plunger whereby to cause said wedge to engage said roller closely adjacent the axial line of the plunger to minimize the lateral thrust of said wedge on said plunger, and anti-friction devices on said frame for engaging the opposite face of said wedge.

3. A press of the character described, comprising in combination a press frame, a reciprocable press plunger operating in said frame, guiding means in said frame for guiding said plunger to reciprocate in a straight line, a reciprocable wedge engaging said plunger to actuate the same on its power stroke, means for reciprocating said wedge transversely of said plunger to advance the plunger on its power stroke, wedge guiding means, said wedge reciprocating and guiding means being carried by said frame and inclined toward the plunger axis in the direction of the power stroke of the plunger to cause said wedge to engage said plunger at a point beyond the line of the plunger axis in the direction of the power stroke of said wedge to provide a component of force transversely of said plunger counterbalancing the opposite frictional thrust of said wedge on said plunger.
